WIRE WRAPPING TOOL

Elsworth T. James, 334 Fuller St., Redwood City, Calif.
Filed Sept. 28, 1960, Ser. No. 59,057
4 Claims. (Cl. 140—124)

This invention relates to a wire wrapping tool and more particularly to a wire wrapping tool for wrapping one or more wires on a terminal or tab of the type having a hole therein to receive the wire.

In making electrical connections from components to tube sockets, terminal strips, connectors and the like, it is often desirable and sometimes required that the wires of the components be wrapped or twisted around the tab or terminals of the tube sockets or terminal strips before the soldering operation is performed so as to make possible a better electrical connection and also to ensure that a good electrical connection is formed between the wire and the terminal or tab. Heretofore, this wrapping operation has been normally performed by hand. Tools which have been developed for such an operation have been found to be unsatisfactory because they require that the terminal posts or tabs to which the wires are connected be able to withstand substantial twisting forces or torques. Conventional terminals and the tabs have not been able to withstand such torques. There is therefore a definite need for a new and improved tool for performing such twisting operations which do not apply torque to the terminals or tabs.

In general, it is an object of the present invention to provide a wire wrapping tool which twists the wire around the terminal or tab without applying torque to the terminal or tab.

Another object of the invention is to provide a wire wrapping tool of the above character in which means is provided for holding the terminal or tab during the twisting operation.

Another object of the invention is to provide a wire wrapping tool of the above character in which the tool can be held in one hand while the wire is inserted into the terminal or tab with the other hand.

Another object of the invention is to provide a wire wrapping tool of the above character in which means is provided for adjusting the depth to which the wire can be inserted into the terminal or tab before the wire is twisted.

Another object of the invention is to provide a wire wrapping tool of the above character which can be readily operated.

Another object of the invention is to provide a wire wrapping tool of the above character which can be economically manufactured.

Additional objects and features of the invention will appear from the following description in which the preferred embodiment has been set forth in detail in conjunction with the accompanying drawing.

Referring to the drawings:

FIGURE 1 is a side elevational view of a wire wrapping tool incorporating my invention.

FIGURE 2 is a front elevational view of my wire wrapping tool.

FIGURE 3 is a side elevational view of the wire wrapping tool with a side cover plate removed.

FIGURE 4 is a top plan view of my wire wrapping tool.

FIGURE 5 is a cross-sectional view taken along the line 5—5 of FIGURE 2.

FIGURE 6 is a cross-sectional view taken along the line 6—6 of FIGURE 1.

FIGURES 7A, 7B, and 7C are taken along the line 7—7 of FIGURE 5 showing various positions of the operating parts of the tool.

2

FIGURE 8 is an enlarged detail view showing the tool being applied to the tab of a connector.

FIGURE 9 is a view showing the tool applied to the tab of the connector with a wire inserted in the tab.

FIGURE 10 is a cross-sectional view similar to FIGURE 9.

In general, my wire wrapping tool for wrapping wire on a terminal or tab having a hole therein to receive a wire consists of means for holding the tab to prevent the application of torque or twisting forces to the tab. This means is formed in such a manner that the wire can be inserted into the tab while it is held by the same. Means is provided for twisting the wire about the tab after it has been inserted in the tab while the tab is held by the holding means. Stop means is provided for limiting the length of wire which can be extended through the tab.

More in particular, my wire wrapping tool, as shown in the drawings, consists of a housing 11 having a side cover plate 12. The housing is substantially in the form of a pistol or gun and is provided with a portion 13 which serves as means by which the tool can be gripped during operation as hereinafter described.

Holding means for the tab or terminal as hereinafter described in the form of a center pin 14 is mounted on the forward portion 16 of the housing 11 and is seated within an internal extension 17 of the housing as shown particularly in FIGURE 5. The end of the center pin 14 is centered within the extension 17 and is squared at 20 to prevent rotation of the center pin with respect to the extension 17. The center pin 14 is provided with a slot 18 which opens into the outer end of the center pin 14 and which lies in the plane which is generally at right angles to the plane of the housing 11. The slot 18 is formed by straight side walls 19 and 21 and a straight bottom wall 22 which inclines upwardly at the rear end thereof as shown particularly in FIGURE 10.

A cylindrical sleeve 23 is rotatably mounted on the center pin 14 and extends into the forward portion 16 of the housing. The sleeve 23 is formed with an extension 24 which is adapted to engage the wire to perform the twisting operation hereinafter described. The extension 24 is provided with a forward face 26 which lies in a generally vertical plane at right angles to the plane of the slot 18 for a purpose hereinafter described. The face extends into a rounded corner 27 which also performs a function in bending or twisting operation as herein-after described. The extension 24 is also provided with an abutment portion 28 which is adapted to engage the extension 14a of the center pin 14 to serve as a stop for the sleeve 23. It will be noted as shown particularly in FIGURE 7A that the extension 24 is formed in such a manner that it does not affect the size of the opening in the center pin provided by the slot 18.

Suitable means is provided for rotating the extension 24 and consists of a rack 31 which is slidably mounted in the housing 11 for vertical movement therein. The rack 31 engages teeth provided on the inner end of the sleeve 23 which form a pinion-like portion 32 on the sleeve. The rack 31 is adapted to be operated by an operating arm or trigger-like member 33 pivotally mounted within the housing upon a pin 34 and engaging a pin 36 mounted on the rack 31. As shown particularly in FIGURE 3, the housing is formed in such a manner that the operating arm 33 can be moved rearwardly by gripping the same and urging it into the space 37 provided in the housing. Means is provided for yieldably urging the rack 31 to its uppermost position and the operating arm 33 to its forward position and consists of a spring 38 having one end connected to the operating arm at 39 and the other end connected to the housing 11 at 41.

An additional cylindrical sleeve 44 is rotatably mounted on the inner sleeve 23. The sleeve 44 is provided with

a collar 46 which is releasably engaged by a cap 47 threaded onto an extension 48 provided on the housing 11. By loosening the cap 47, the outer sleeve 44 can be rotated with respect to the inner sleeve for a purpose hereinafter described. The sleeve 44 is provided with a cut-out 49 so that a semi-cylindrical portion 51 is provided on the forward end of the sleeve for a purpose hereinafter described.

Use and operation of my wire wrapping tool may now be briefly described as follows. Let it be assumed that it is desired to connect wires to a plurality of tabs 56 provided on a connector 57. The tabs 56 are of a type that are provided with elongate openings 58 which are adapted to receive one or more wires to be electrically connected to the tab or terminal 56. In use, the apparatus in which the connection is being made is positioned in such a manner that the tabs lie in a generally horizontal plane. It, however, is not necessary to have the tabs lie in such a plane since the tool is adapted to be moved and used in various positions although not as comfortably. With the tabs in a horizontal plane the tool is grasped with one hand and held in a generally vertical position so that the slot 18 lies in a horizontal plane. The tool is then placed over the tab with the tab seating within the slot 18 in the center pin 14 as shown particularly in FIGURE 9.

Prior to the time that the tool is placed over the tab, it is normally desired to position the outer or additional sleeve 44 in such a manner that it will underlie the opening 58 in the tab after the tool has been placed on the tab. As explained previously, it can be readily positioned by unloosening the cap 47, moving the sleeve 44 to the desired position and then tightening the cap.

With the outer sleeve 44 in the proper position and with the tool mounted on the tab, the other hand grasps the wire to be connected to the tab and inserts it through the hole 58 in the tab until it engages the portion 51 of the outer sleeve. While holding the wire in this position as shown in FIGURE 7A, the operating arm 33 of the tool is gradually moved inwardly into the housing to cause downward movement of the rack 31 and counterclockwise rotation of the inner sleeve 23 as viewed in FIGURE 7A. Counterclockwise rotation of the sleeve 23 causes the face 26 to move into engagement with the lower end of the wire 61 and to cause the lower end of the wire to be twisted about the tab in the manner shown in FIGURES 7B and 7C. The rounded corner portions 27 provided on the extension 24 ensures that a smooth bend will be placed in the wire as it is wrapped about the tab. Rotation of the sleeve 23 is continued until the extension 24 engages the extension 14a provided on the center pin. As shown in the drawing, the inner sleeve 23 is rotated through approximately 270° to place a bend in the wire 61 so that it is firmly wrapped about the terminal or tab. During the time that the wire is being wrapped about the tab, the tab is being held by the center pin 14 so that it cannot be twisted.

As soon as the wrap has been completed, the operating arm 33 is released and the sleeve 23 is returned to its own initial position as shown in FIGURE 7A by the spring 38. The tool can then be removed from the tab after which the wire 61 can be soldered in place. If desired before soldering, other wire can be wrapped on the tabs.

With such a tool, it can be seen that excellent electrical connections can be made. First a very good physical connection is made by the tool after which the connection is improved by the application of solder. It can be seen that the tool is readily constructed in such a manner that it can be readily used by women who normally perform such work in the assembly of electronic apparatus. The tool makes it possible for the worker on the production line to first wrap all of the wires on the terminals and then to solder the wires. Heretofore, it has been necessary for the worker to first wrap the wire

on the terminal with a pair of pliers and then to lay down the pliers and pick up a soldering iron and perform the soldering operation.

The tool makes it possible to mechanically fasten the wire to the tab merely by one operation of the hand; that is, by pulling the operating arm 33.

It is apparent from the foregoing that I have provided new and improved wire wrapping tool which is particularly adapted for production line work and which makes it possible to wrap wires onto the terminals or tabs without placing any torque or twisting forces to the tabs. This is particularly important in view of the fact that the tabs are generally formed of relatively light material which is readily deformed.

I claim:

1. In a wire wrapping tool for wrapping wire on a terminal or tab having a hole therein adapted to receive a wire end, a center pin, the center pin being formed with a slot extending longitudinally of the center pin and extending out one end of the center pin, said slot being adapted to receive the terminal or tab and to prevent rotation of the terminal or tab within the slot, a sleeve-like member rotatably mounted on the center pin for movement between the first and second positions, said sleeve-like member having only one portion extending beyond said one end of the center pin, said portion being formed to subtend only a relatively small angle in comparison to the total circumference of the sleeve-like member, said portion also being formed with a substantially planar face extending at substantially right angles to the longest dimension in cross-section of the slot and substantially equidistant between the extremities of said longest dimension when said sleeve-like member is in said first position so that the wire end can be inserted in the hole in the terminal or tab in a direction at substantially right angles to the longitudinal axis of a sleeve-like member while the tab is held by the center pin and so the wire end will overlie said face, said portion also having a substantially curved face adjoining said substantially planar face and being immediately adjacent said slot when said sleeve-like member is in said first position, said substantially curved face and said substantially planar face being adapted to engage the wire end after the wire end has been inserted through the hole in the terminal, and means for rotating the sleeve-like member with respect to the center pin from said first to said second position to cause said substantially curved face and said substantially planar face to engage the wire end and to twist the wire end about the terminal or tab while retaining the center pin in a stationary position to prevent twisting of the terminal or tab as the wire is twisted about the terminal or tab.

2. In a wire wrapping tool for wrapping a wire on a terminal or tab having a hole therein adapted to receive a wire end, a center pin, the center pin being formed with a slot extending longitudinally of the pin and opening through the top side of the pin and one end of the pin, said slot being formed to receive a terminal or tab, a sleeve-like member rotatably mounted on the center pin and covering the top side of said slot, said sleeve-like member having a portion extending beyond said one end of said center pin, an additional sleeve-like member rotatably mounted on the first named sleeve-like member, said additional sleeve-like member extending beyond said one end of the center pin and having a cut-out portion extending longitudinally of the additional sleeve-like member, yieldable means for retaining the first named sleeve and the portion carried thereby in a predetermined position with respect to the center pin so that the wire end can be inserted through the hole in the terminal in a direction at right angles to the longitudinal axis of the center pin while the terminal is being held by the center pin, the cut-out in the additional sleeve being positioned so that the wire end can be inserted through the hole in the terminal from one side, said

additional sleeve being engaged by the wire end after it is inserted through the hole in the terminal to limit the length of wire which can be extended through the terminal, and means for rotating the first named sleeve-like member with respect to the center pin against the force of the yieldable means to rotate said portion into engagement with the wire end and to thereafter continue rotation of said portion to twist the wire end about the terminal while at the same time retaining the center pin in a stationary position to thereby prevent twisting of the terminal as the wire end is twisted onto the terminal.

3. In a wire wrapping tool for wrapping wire on a terminal or tab having a hole therein adapted to receive a wire end, a center pin, the center pin being formed with a slot extending longitudinally of the center pin and extending out one end of the center pin, said slot being adapted to receive the terminal or tab and to prevent rotation of the terminal or tab within the slot, a sleeve-like member rotatably mounted on the center pin and having a portion extending beyond said one end of the center pin, the portion being formed so that the wire end can be inserted into the hole in the terminal or tab in a direction substantially at right angles to the longitudinal axis of the sleeve-like member while the terminal or tab is being held by the center pin, said portion being adapted to engage the wire end after the wire end has been passed through the hole in the terminal or tab, means for rotating the sleeve-like member with respect to the center pin to cause said portion to engage the wire and twist the wire end about the terminal while retaining the center pin in a stationary position to prevent twisting of the tab as the wire is twisted about the terminal, and an addi-

10 tional sleeve-like member rotatably mounted on the first named sleeve-like member, said additional sleeve-like member having a portion extending beyond said one end of the center pin, said additional sleeve-like member having a cut-out extending longitudinally of the additional sleeve-like member and serving to expose the terminal placed in the center pin so that the wire end can be placed through the hole in the terminal in a direction at right angles to the longitudinal axis of the additional sleeve-like member during the time the terminal is held by the center pin, said additional sleeve-like member serving to limit the length of wire which can be extended through the terminal.

15 4. A wire wrapping tool as in claim 3 together with a housing supporting said center pin, said first named sleeve-like member and said additional sleeve-like member, said housing being in the form of a pistol and wherein said means for rotating the first named sleeve-like member with respect to said center pin includes an operating lever movable into and out of the housing, a vertically reciprocating rack operated by said lever, and a pinion secured to said first named sleeve and engaging said rack and being driven by said rack to rotate said first named sleeve-like member.
